US00D482412S

(12) **United States Design Patent** (10) Patent No.: **US D482,412 S**
Manville (45) Date of Patent: ** *Nov. 18, 2003

(54) **DESIGN CRAFT KIT CONSTRUCTION COMPONENT—TRANSPARENT/TRANSLUCENT TEAR-DROP FORM**

(75) Inventor: **Richard B. Manville**, Los Angeles, CA (US)

(73) Assignee: **Mattel, Inc.**, El Segundo, CA (US)

(*) Notice: This patent is subject to a terminal disclaimer.

(**) Term: **14 Years**

(21) Appl. No.: **29/157,957**

(22) Filed: **Mar. 26, 2002**

(51) LOC (7) Cl. **21-01**

(52) U.S. Cl. **D21/484; D21/386; D21/493**

(58) Field of Search .... **D6/511; D17/20; D20/22, 23, 27, 28, 29; D21/386, 390, 478-480, 484, 489-492, 504, 505; 84/332; 273/157 R; 446/85, 87, 102, 113; 434/81, 82**

(57) **CLAIM**

The ornamental design for a design craft kit construction component—transparent/translucent tear-drop form, as shown and described.

DESCRIPTION

FIG. 1 is a perspective view of the invention; and, FIG. 2 is a plan view of the invention.

1 Claim, 1 Drawing Sheet
